RICHARD HAMMERLY, OF BALDWIN, NEW YORK

ELECTRIC-LIGHT FIXTURE

Application filed June 28, 1928. Serial No. 288,999.

My invention has for its object to provide an electric light fixture so constructed as to make it possible to readily secure it to a stud or support at an outlet without twisting the electric light wires which connect the outlet with the electric light fixture.

Another object of my invention is to construct the electric light fixture in two parts, one of which may be screwed to or otherwise secured to the stud at the outlet, the other part of the electric light fixture being constructed to contact with the first part and being held thereto by means provided without turning the first part relatively to the second part.

Still another object of the invention is to provide, when desired, some freedom of movement between the body of the electric light fixture and the part secured to the stud at the outlet so that when the stud is in the ceiling and is out of alignment the body of the electric light fixture will nevertheless be disposed perpendicularly.

Additional objects of the invention will appear in the following specification, in which the preferred form of my invention is described.

In the drawings similar reference characters refer to similar parts in all the views, in which

Fig. 1 is a fragmentary view, partly in section, showing how the electric light fixture is secured to a ceiling.

Fig. 2 is a sectional view of Fig. 1.

Fig. 3 is a sectional view on the line 3—3 of Fig. 2.

Fig. 4 is a fragmentary view showing a modified form of the invention.

Fig. 5 is a sectional view on the line 5—5 of Fig. 4.

The electric light fixtures which are now being used are provided with threads which mesh with the threads on the stud at the outlet, and when the fixture as a unit is screwed in place the electric light wires connecting the outlet with the electric light fixture are twisted, which often damages the insulation thereby causing a short circuit. This is avoided in the electric light fixture which is the subject-matter of this application for in using the fixture which is described in this

specification there is no possibility of twisting the electric light wires or otherwise damaging the insulation.

By referring to the drawings it will be seen that a bracket 10 is provided with an inner thread 11 which is adapted to mesh with an outer thread 12 on a stud 13 which, as shown in Fig. 1 of the drawings, depends from the ceiling 14 but which may be in a sidewall as will be readily understood. To the bracket 10 there is secured a hollow member 15 by means of a screw 16, the head of the screw 16 engaging shoulder 17 at the inner side of the hollow member 15, as best seen in Figs. 2 and 4 of the drawings. This screw 16 meshes in a threaded opening 18 in the bracket 10. It will be understood that there may be some play between the hollow member 15 and the bracket 10 so that if the stud 13 is out of alignment the body of the fixture 70 will nevertheless assume a perpendicular position. However, when a wall fixture is to be held in place, the hollow member 15 may be secured rigidly to the bracket 10 by constructing the parts so that the head of the screw 16 will press the hollow member 15 firmly against the bracket 10.

The hollow member 15 is provided with one or more, preferably a plurality, of openings 19, through one or more of which the electric wires 20 may extend, and there are slots 21 in the hollow member 15 which extend from the said openings 19 to the outer end 22 of the hollow member 15. The hollow member 15 has inner threads 23 and outer threads 24 at its said slots 21.

In connection with the hollow member 15 there is provided a tubular member 25 which is a part of the body of the electric light fixture. This tubular member 25 has an inner thread 26 at its inner end, it being possible to push the said inner end of the tubular member 25 with the outer thread 26 within the outer end of the hollow member 15, the slots 21 permitting a free movement of the portions of the hollow member 15 between the said slots. When the tubular member 25 is in position, as shown in Fig. 2 of the drawings, a nut 27 which meshes with the outer thread 24 on the hollow member 15 and

which acts as a binder may be screwed down to grip the portions of the hollow member 15 between the slots 21 to press the said portions of the hollow member with the inner threads 23 against the outer thread 26 at the end of the tubular member 25.

In using the electric light fixture, the bracket 10 carrying the hollow member 15 is screwed to the stud 13 when the wires 20 are disposed through the openings 19 and out of the outer end of the hollow member 15 through the tubular member 25, where they are connected with the electric light fixture in the customary manner. When this has been done the nut 27 having been turned away from the outer end of the hollow member 15, the end of the tubular member 25 with its screw 26 is pressed in the outer end of the hollow member 15 when the nut 27 is turned to grip the outer end of the hollow member 15 with its inner thread 23 locking with the outer thread 26 on the tubular member 25.

In the modified form of the invention, shown in Figs. 4 and 5, instead of the outer thread 24 and the nut 27 a strap 28 is employed which has terminals 29 with a screw 30 passing through an orifice 31 in one of the terminals and meshing with a threaded opening 32 in the other terminal, so that with the tubular member 25 in position the terminals 29 of the strap 28 may be drawn together by the said screw 30 to hold the hollow member 15 between the slots 21 with the inner thread 23 against the outer thread 26 on the tubular member 25.

I claim:

1. In an electric light fixture, a bracket adapted to be attached to a stud at an outlet, the bracket having a threaded opening, a member having an opening therethrough, the member having an inner shoulder adjacent one of its ends, a screw meshing in the threaded opening in the bracket and provided with a head engaging the inner shoulder in the member for adjustably securing the member to the bracket, the member having an opening for an electric light wire and a longitudinal slot extending from the opening through its other end, a body member having an end adapted to be inserted in the last-mentioned end of the member and means to press the member against the end of the body member for holding the body member in position.

2. In an electric light fixture, a bracket adapted to be attached to a stud at an outlet, the bracket having a threaded opening, a member having an opening therethrough, the member having an inner shoulder adjacent one of its ends, a screw meshing in the threaded opening in the bracket and provided with a head engaging the inner shoulder in the member for adjustably securing the member to the bracket, the member having an opening adjacent its said end for an electric light wire and a slot extending from the open-

ing through its other end, the member beyond the opening and to its said other end being of increased diameter and exteriorly threaded, the said other end of the member being open, a body member having an end normally disposed in the said other end of the member and a nut adapted to be disposed freely around the member at its opening and to mesh with the thread on the member, permitting the turning of the nut in the thread on the member to grip the body member by the member.
